US00D987220S

(12) **United States Design Patent** (10) **Patent No.:** **US D987,220 S**
(45) **Date of Patent:** **** May 23, 2023**

(54) **SCRAPING BOARD**

(71) Applicant: **Haiyan Zhao**, Shenzhen (CN)

(72) Inventor: **Haiyan Zhao**, Shenzhen (CN)

(**) Term: **15 Years**

(21) Appl. No.: **29/850,820**

(22) Filed: **Aug. 23, 2022**

(51) LOC (14) Cl. **07-05**

(52) U.S. Cl.

USPC **D32/46**; D24/214; D24/215

(58) **Field of Classification Search**

USPC D32/46; D4/118, 137; D7/698; D8/16;
D24/214-215, 231; D58/157

CPC A61H 7/003; A61H 7/007; A61H 39/04;
A61H 2205/00; A61B 17/14; B66F 15/00
